Property (USA) Office(57) **CLAIM**

The ornamental design for a lighting unit for vehicle light, as shown and described.

DESCRIPTION

FIG. 1 is a front, right side and top perspective view of a lighting unit for vehicle light showing the claimed design; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, left side and bottom perspective view thereof.

The dashed broken lines in the drawing depict portions of the lighting unit for vehicle light that form no part of the claimed design.
